UNITED STATES PATENT OFFICE

1,922,977

CIRCULAR KNITTING MACHINE

Albert E. Page, Brooklyn, N. Y., assignor to
 Scott & Williams, Incorporated, New York,
 N. Y., a Corporation of Massachusetts

Application August 31, 1932. Serial No. 631,249

10 Claims. (Cl. 66—40)

This invention relates to a circular knitting machine having independent needles, and more particularly to mechanism for producing a wide variety of stitches thereon. One of the objects 5 of the invention is to produce a machine capable of making hosiery containing tuck stitches and float stitches in the same stocking at any desired parts of the stocking and on all or selected portions of the needle circle. In a machine made 10 according to the invention the regular stitch cam can be lowered to tucking position and there are a multiplicity of means for giving this movement.

In the drawings the invention is shown embodied in a Scott & Williams revolving needle 15 cylinder hosiery machine of the general type set forth in the patent to Robert W. Scott No. 1,152,850, dated September 7, 1915, and in the patent to Robert W. Scott No. 1,282,958, dated October 29, 1918.

20 In the drawings,

Figure 1 is a view of a stocking containing tuck and float stitches made on a machine containing the new attachment;

Figure 2 is a diagrammatic view illustrating the 25 interlooping of the yarns of the stocking of Figure 1, the top portion of the view showing the stitch formations in the welt, while the lower portion of the view shows the stitch formation in the body of the leg of the stocking;

30 Figure 3 is a development of part of the cam cylinder, needles and jacks, when adjusted to make a tucked picot edge, the needles moving from right to left in the direction of the arrow;

Figure 4 is a development similar to Figure 3, 35 showing the cam cylinder, needles and jacks adjusted to make a partial float stitch; the solid line position of the right-hand stitch cam being the position of this cam when making a partial float stitch;

40 Figure 5 is a plan view of the head of the machine taken on a line above the bed plate, showing the various cams which engage the needle butts and the levers more directly associated therewith;

45 Figure 6 is an elevation partly in section from the front of the machine showing the pattern chain and cams on the pattern chain shaft which control the leading stitch cam;

Figure 7 is an elevation from the left side of 50 part of the machine, showing some of the levers controlling the lowering of the leading stitch cam;

55 Figure 8 is a detail showing the rocking cam on the high speed gear for making the partial float courses in the leg; while

Figure 9 is a development of the cam paths on the main pattern drum for the levelling cam, the finger for the heavy yarn and the auxiliary clearing cam, the paths being shown with cams, one below the other, which act simultaneously; the three thrust rods being shown one below the other in the positions which they occupy during the making of the float stitch pattern in the welt.

Referring first to the fabric which can be made on this novel machine, in Figure 1 I have shown 60 a stocking with an inturned welt, such as referred to in the above-mentioned patent to Robert W. Scott No. 1,282,958, there being a picot edge 732 formed by tucking on alternate needles for four courses, so that when the needle is 65 finally cleared there are four loops accumulated. In the welt are shown a group 733 of two horizontal stripes, a group 734 of three stripes and a single horizontal stripe 735, each stripe being formed by floating the heavier of the two yarns 70 on alternate needles for two courses. The leg of the stocking is formed by knitting first two courses 727, 728 in which the heavy yarn 729 is floated in alternate wales, and then two courses 75 830, 831, in which both yarns are knit in; the intervening wales in all courses being knit of both yarns. In this way an ornamental structure 80 736 such as is shown in the lower half of Figure 2, is obtained. This is similar in part to the patent to Frederick W. Smith No. 1,772,230, dated 85 August 5, 1930.

Various stitches can be obtained by manipulating the needles, jacks and knitting cams in the manner shown in Figures 3 and 4. In Figure 3 is shown the adjustment of the various parts 90 for knitting tuck stitches on alternate needles. In this figure the needles are moving from right to left. The needles at the normal level N do not clear their latches. There is a leading stitch cam 361 shown in lowered position. The needles 95 on the part of the needle circle which knit the heel have short butts, while those which knit the instep have long butts. Every alternate needle in the circle has a jack 380 below it, the intervening needles being jackless. The long butt jackless needles are designated by the reference character n^1 , while the short butt jackless needles are marked with the character n^2 . All the needles having jacks are indicated by the character n^1 , whether long or short butt. The function of 100 the jacks 380 is to raise their needles to the clearing point, one purpose being to produce tucking on intervening needles. The jacks 380 are manipulated by a cam 366 located in the jack cam path at a point just after the usual 105 110

needle switch cam 415. The jacks riding up their cam 366 raise their needles n^1 to the clearing point, whereas the other or tucking needles n^2 and n^3 approaching at normal level N are not cleared. These tuck needles pass under the top center cam 357, keeping the yarns in their hooks, and ride down under the regular stitch cam 360. When they pass the throat plate, their hooks are high enough to take new bights of yarn from both of the yarn fingers F^1 , F^2 . The auxiliary clearing cam 842 shown at the left of Figure 3 is retracted during the knitting of tuck stitches.

When it is desired to float the heavier yarn 729 on alternate needles, the parts are adjusted 15 as shown in Figure 4. In this case the yarn finger F^1 , which feeds the heavier yarn 729, is raised slightly so that needles which approach the throat plate at the tucking level do not receive this heavier yarn. However, in order to get 20 float stitches rather than tuck stitches, it is necessary to have the auxiliary clearing cam 842 inserted to operative position as shown in Figure 4. This cam raises all the needles to the cleared level. Because it is desired that only alternate 25 needles take both yarns, a levelling cam 822 is inserted to draw all the needles down to the normal or tucking level N after they have been cleared by the auxiliary cam 842 and just prior to the time that the jacks riding up their cam 366 begin to raise their needles to the cleared level. In this way all the needles are cleared 30 and then brought down to the tucking level and the needles n^1 having jacks thereunder are immediately returned by the jacks to the clearing 35 point where they get both yarns. The stitch cam 361 being lowered as shown in solid lines, and the needles n^2 and n^3 having no jacks, they remain at the tucking level after having been brought down by the levelling cam 822 and take 40 only the lighter yarn 730 fed from the yarn finger F^2 . The general idea of feeding one yarn from a slightly higher level than the other in order to cause floating of one of the yarns, is shown in 45 the patent to E. A. Hirner No. 1,026,910, dated May 27, 1913.

In order to get the ornamental structure shown in the lower part of Figure 2 or the groups of stripes 733, 734, 735 in the welt, two courses are made as described above and then one or more 50 courses are made with both yarns knit in on all needles. The alternate two courses float and two courses plain can be repeated as many times as desired. In Figure 1 the entire leg is made this way. In order to cause both yarns to be knit 55 on all needles when the parts are adjusted as in Figure 4, it is necessary merely to raise the leading stitch cam 361 to its normal level, i. e., the position shown in dotted lines in Figure 4. If it is desired to make an instep having fabric such as shown in the lower part of Figure 2— 60 where two plain courses are alternated with two courses in which the heavier yarn is floated on alternate needles—and at the same time knit a plain sole on the stocking, it is then necessary merely to withdraw partially the levelling cam 822 shown at the right of Figure 4 until it misses the short butt needles but remains in contact with the long butt needles. In this way the long 65 butt jackless needles n^3 are brought down to the tuck level by the levelling cam 822 as heretofore and therefore they miss the heavier yarn 729. The short butt jackless needles n^3 on the sole pass the levelling cam 822 without being lowered 70 and all the needles on the sole approach the

throat plate at the clearing point and take both 80 yarns.

Turning now to the machine which produces such fabrics, it should be noted that mechanism has been provided by which the regular right-hand stitch cam 361 is lowered whenever any fancy stitches are desired, and a multiplicity of controls for this cam and the other knitting cams involved are provided in such a manner that selective control is provided either at long intervals 85 or at recurrent short periods, without adding to the number of basic control elements in the machine.

Referring first to the making of tuck stitches, 90 it will be recalled that it is necessary merely to keep the leading stitch cam in its lowered position, as shown in Figure 3, for four courses. In the machine shown in the drawings, when the picot edge is desired the clearing cam is lowered under the control of the main pattern chain 85 of the machine by means of a high lug 336 on a link on that chain. Before describing the connection for this purpose between the pattern chain and the clearing cam, it is desired to point out that this pattern chain not only provides 100 this picot edge selection but initiates and stops a recurrent movement of the clearing cam when making float stitch stripe. To make the picot edge the high lug 336 on the chain operates levers which lower the clearing cam and hold it down 105 for four courses until the chain is racked forward once more. In the Scott & Williams machine this racking of the pattern chain occurs every four courses. If, in a machine whose chain is adjusted in this manner, it is desired to have a 110 picot edge formed by a two-course tuck, this can be done by employing the tucking mechanism shown in the Page Patent No. 1,337,425, dated February 1, 1921, or by use of the high speed gear 65, as described below. 115

The lever mechanism for this tucking comprises the following: There is an arm 368 overlying the edge of the pattern chain where the high lugs 336 are located, namely, the left side 120 of the chain as one faces the front of the machine. This chain reading arm 368 is part of a bracket 370 pivotally mounted on a rod above the pattern chain running parallel to the pattern chain shaft. The arm 368 is pressed toward 125 its down position by a tension spring 369. At the left end of this bracket 370 is a lifting bar 846 passing upwardly to a position opposite the bed plate B of the machine, this lifting bar 846 being pivotally attached to the middle of a raising arm 844. The left end of this raising arm is 130 pivoted to the bed plate B and its right-hand end, underlies an operating lever 719 for the right-hand stitch cam 361. (See Figures 5 and 6). This operating lever 719 is pivoted intermediate 135 its ends, with the result that when the bar 846 moves upwardly the clearing cam is lowered. It should be noted that there is a small space between the raising arm 844 and the clearing cam operating lever 719 when the arm 368 is on the surface of the chain links as shown in Fig. 6, showing that it is only the last part of the upward movement of the raising bar 846 which actuates the clearing cam. This concentration of the effective action of the raising bar 846 in the last 140 part of its movement is necessary in order that the pattern chain or the pattern chain shaft may be used to initiate and stop the operation of the clearing cam 361 at the beginning and end of a series of recurrent operations, as for instance, in 145 making the pattern of the leg of the stocking 150

shown in Figures 1 and 2, while permitting the clearing cam to be raised and lowered during this period.

I now have described the positive and direct control of the clearing cam from the pattern chain in which the pattern chain holds the clearing cam down in its lowered position as long as the high lug on the pattern chain is under the chain reading arm 368, to make the tuck picot edge. I will now describe the two permissive controls exercised over that clearing cam by the pattern chain and the pattern chain shaft respectively.

The permissive control obtained direct from the pattern chain is caused by low lugs 837 on the pattern chain coming under the pattern chain reading arm 368, the lifting movement given to the reading arm 368 by a low lug not being sufficient to cause the arm 844 to lower the clearing cam directly. This raising of the pattern chain reading arm 368 by a low lug on the pattern chain is of course received by the entire bracket 370 and is transmitted to a clutch actuating rod 522 which passes upwardly to a position about on a level with the arm 844 but to the right of same. This clutch actuating rod is designed to connect and disconnect certain racking mechanism with the clearing cam operating lever 719 so as to provide recurrent movements of the clearing cam for formation of stripes in the welt. In the drawings the racking mechanism which is adapted to lower the clearing cam for two courses and then release same is operated from the high speed or plate gear 65 at the right side of the machine, which is a gear revolving continuously, making one revolution for every four revolutions of the cylinder. On the outer edge of this gear wheel is a cam 66 and in its path lies the racking lever 307. Through an extension 308 of this racking lever 307 and a racking lever 725 the indications of the cam 66 on the plate gear 65 are transmitted to a pawl 723 to which the racking lever 725 is fastened by a pin 526. This pawl is pivoted about an axis 520, the pawl being directly on top of a bell crank lever 720 which constitutes an actuating cam for the clearing cam operating lever 719. One arm of this bell crank lever or actuating cam underlies the pawl 723 and the other arm underlies a lug 724 on one side of the operating lever 719. This lug 724 is located on the opposite side of the pivot point of the lever 719 from the clearing cam so that when one arm of the bell crank lever 720 pushes underneath this lug 724 the clearing cam will be lowered. The pivot point 520 is so located that when the cam 66 actuates the racking lever 307 the actuating lever 720 if moved in unison with the racking arm 725 would cause the clearing cam to be lowered.

The control of these means by the pattern chain is by virtue of the connection from the clutch rod 522 and the actuating lever 720 to the pawl 723. The upper end of the clutch rod 522 coming from the pattern chain bracket 370 passes upwardly through a hole in the actuating lever 720 and when the reading arm 368 is raised by a low lug on the pattern chain the upper end of this clutch rod 522 projects above the surface of the cam 720. When the reading arm 368 has not been raised by a link on the pattern chain, the upper end of the rod 522 is flush with or lower than the upper surface of the cam 720. The pawl 723 lying directly on the upper surface of the actuating cam 720 is notched at its outer end in such a manner as to leave clear that portion of the surface of the actuating cam 720 through

which the upper end of the rod 522 projects, except at such times as the pawl is given a movement by the racking arm 725. There is a projection or notch 721 on the outer end of the pawl 723 which will engage the upper end of the rod 522 when that rod is raised and the pawl is moving to the right by the racking arm 725. It will be obvious then that when the racking arm 725 under the influence of the cam 66 on the high speed gear 65 swings the pawl toward the right, this notch 721 will catch on the upper end of the rod 522, pivot the bell crank lever 720 to the right, bringing one arm of that lever under the lug 724 on the operating lever 719 and causing the clearing cam to be lowered. As already pointed out, the low lug on the chain will underlie the chain arm 368 during four revolution of the needle cylinder, but the control of that low lug being permissive, as distinguished from the control of the high lug, the actual length of time that the clearing cam is lowered is determined by the racking mechanism just described and the cam 66 is preferably made of such length that the clearing cam is lowered for only approximately two revolutions of the needle cylinder.

In order to make the fabric of the leg of the stocking where there are, recurrently, two courses of special stitches and two courses of plain stitches throughout the leg, the racking mechanism just described is made use of, but instead of having a series of low links on the chain, special cams are provided on the shaft on which the pattern chain is mounted. As can be seen from a glance at Figure 6, the pattern chain, carried by its usual sprocket wheel 84, is mounted on a pattern chain or clutch shifting shaft 80, as usual. As explained in the patent to Robert W. Scott No. 1,152,850 above-mentioned, sprocket wheel 84 turns loosely on its shaft 80, the shaft 80 being turned by means of a pawl controller 83, a main pawl and a rack wheel (not shown), which rack wheel is tight on the shaft 80. The shaft 80 makes one revolution for each complete stocking knit and the chain also makes one revolution during that time. The main pattern drum 120 and the shaft 80 are racked around together. On the left end of this shaft is a gear 479 which is in the train of gears driving the usual main pattern drum 120, and carried on the left side of this gear 479 is a disk 480 on which there are cams 481, 482. Referring to Figure 7, the cam 482 corresponds to the leg of the stocking and the cam 481 corresponds to the instep, the space between the two cams being taken up by the racks due to the making of the heel. These cams 481, 482 are read by a chain reading arm extension 838 unitary with the chain reading bracket 370. These cams are so adjusted that the amount of movement which they cause the chain reading bracket 370 is equivalent to a low lug on the pattern chain and these cams are positioned to raise the clutch rod 522 into operative position during such portions of the knitting of the leg and foot as it is desired to have fancy stitches made. In describing the stitch cam adjustments in Figures 3 and 4, reference is made to the auxiliary clearing cam 842 and to the fact that when tuck stitches are desired this auxiliary clearing cam is retired and when the special float stitches are desired this cam is brought into action. This auxiliary clearing cam is controlled from the main pattern drum 120 by mechanism which is shown in Figure 5. This mechanism consists of a thrust rod 840 operated by the cam on the

main pattern drum 120, a wire 841 connecting the upper end of that thrust rod with the bracket 839 which carries the auxiliary clearing cam 842. There is a spring 608 fastened to the bracket 839 tending to pull that clearing cam into operative position and when the thrust rod 840 is pivoted by a cam on the main pattern drum, it pulls the auxiliary clearing cam away from the needles into idle position.

10. In order to produce the kind of stitches previously described, it is necessary not only to have this auxiliary clearing cam and this movement of the main clearing cam, but also to have a switch cam levelling cam and to actuate it radially. This cam is located in and carried by the same bracket as the switch cam and is adapted to lower from the clearing point to the tuck or normal level N all needles in whose path it lies. When it is desired to make tuck stitch, this cam has no effect on the needles because the needles approach it at the tuck level and when making float stitch around the entire circumference of the needle circle, the cam affects all the needles which approach it, because they have all been cleared by the auxiliary clearing cam 842, just referred to. Normally, therefore, this cam is radially, at its innermost position, engaging the butts of all the needles. Assuming that the machine carries needles with butts of different lengths and that one of the purposes in having these butts of different lengths is to enable the machine to throw the instep needles out of action when knitting the heel pocket, it is necessary to vary the position of this levelling cam in order to make a plain sole in combination with an instep having fancy stitches—assuming that the instep needles are the ones with long butts. It is therefore necessary to retire this levelling cam half way until it is beyond the path of the short butt needles but still lies in the path of the long butt needles. The mechanism for controlling this levelling cam is shown in Figures 5, 6 and 7, the control being effected primarily from the main pattern drum. I have shown this control from the main pattern drum combined with the pattern drum control which is sometimes used for other purposes, such as shown for instance in the patent to Robert W. Scott, No. 1,641,101, where it is used for an auxiliary feed cam lever, but my description here will be confined to such parts of this combined mechanism as affect the levelling cam. As already mentioned, the levelling cam is carried by the bracket 411 in which the switch cam is mounted and the levelling cam is radially movable. Fastened to the rear end of one side of this cam is a small wire 827 which passes outwardly to a point near the outer edge of the bed plate B. Here the outer end of the wire passes through a levelling cam retracting arm 825, there being a screw sleeve on the wire just outside the arm 825, so that when the arm 825 is moved radially outward it will exert an outward pull on the wire 827. This arm 825 is carried by a pivoted lever 829 whose other end engages a cam face 461 on the upper end of a thrust rod 460 and this thrust rod and cam face are so arranged that when the thrust rod is raised the arm 825 is moved radially inward. When this arm is thus moved radially inward it presses against a light compression spring 826 on the wire, which in turn presses the levelling cam 822 radially inward. When the thrust rod 460 is dropped the lever and arm 825 move about the pivot of the lever and the arm 825 catching against the sleeve on the wire retracts the levelling cam. This retracting move-

ment is caused by a tension spring 726 stretched between the arm 825 and the racking lever 725 of the racking mechanism. By arranging this mechanism in the manner just described and as shown in the drawings, it is possible to combine the controlling functions of both the levelling cam and the auxiliary feed cam lever in the one thrust rod operating from the main pattern drum 120.

15. The switch cam levelling cam 822 and the switch cam 415 itself are both carried by the usual switch cam bracket 411 mounted on the bed plate B, the levelling cam being mounted on one side of the bracket and being limited by the bracket to a movement between its forward position, where it engages the butts of all the needles, and a retracted position, where it will engage only the long butt needles. The switch cam is operated in the customary manner by means of the vertical gravity rod 216 taking under the wing or tail 409 of the switch cam collar. The vertical gravity rod 216 is controlled from the main pattern drum 120, as usual.

20. With reference to the exact mounting of the right-hand stitch or clearing cam 361, I have mounted this in a slightly different manner from that shown in the Page Patent 1,367,425, above referred to, and instead of pivoting the cam about one end, I prefer to raise and lower the entire cam, both the pins on which the cam is mounted lying in slots and the cam being fixed with relation to the operating lever 719.

25. The construction of the machine having been set forth, its operation will now be described. Assuming that the machine is knitting from top to toe, the machine will start knitting the welt first, and for purposes of illustration it will be assumed that the machine is going to knit an automatic inturned welt in a manner similar to that in the machine described in the patent to Robert W. Scott, No. 1,282,958, above-referred to. In that patent the machine is started up from the bare needles first by feeding the yarn to every other needle for one course by means of selecting needles through use of the jacks, and then to all the needles, and subsequently having loops held on the transfer jacks in the dial of the machine while the welt is being formed. The dial and transfer jacks are not shown in these drawings, these being well known to the art and shown and explained in the Robert W. Scott Patent No. 1,282,958. During the knitting of that portion of the welt which is to form the inner side of the fold of the usual doubled welt, the yarn finger F¹ is down on the throat plate and both yarns are being fed to all the needles. The bracket 370 is in its lowermost position, there being no lugs underneath the chain reading arm 368 and no cam under the pattern shaft reading arm 838. The spring 608 therefore holds the stitch cam 361 in its normal raised position where it clears all the needles. With the bracket 370 in its lowermost position, the clutch actuating rod 522 does not affect the stitch cam 361. The thrust rod 460 for the levelling cam 822 lies on the low cam 824, causing the levelling cam 822 to be in. However, since all the needles are cleared by the stitch cam 361, there is no selection and all needles knit both yarns. During this time the auxiliary clearing cam 842 is held out of action by the cam 845 on the pattern drum. When it is time to make the picot edge 732, a high lug 836 comes under the reading arm 368, raising the lifting bar 846 and the raising arm 844 to their highest positions, thus low-

ering the stitch cam 361 to its tuck position (see Figures 3 and 7). The levelling cam 822 is still held off the surface of the main pattern drum by cam 824. The thrust rod 840 for the auxiliary clearing cam 842 is still on the cam 845 holding the auxiliary clearing cam 842, withdrawn, as shown in Fig. 3. The selection of needles by the jacks, after passing the levelling cam 822, therefore becomes effective to cause tucking for whatever number of courses it is desired to have in the picot edge. If it is desired to make this picot edge by means of tucking for two courses instead of four—as would be obtained by using a high lug 836 on the pattern chain without any other mechanism—a low lug 837 on the pattern chain can be used, and the cam 66 on the high speed gear 65, acting through the racking rod 725 and the clutch mechanism 720, 723, would cause lowering of the clearing cam 361 for only two courses instead of four.

After the picot edge, the pattern chain and the pattern drum are racked ahead and the pattern chain reading arm 368 falls off its lug, returning the stitch cam 361 to its normal position, shown in dotted lines in Fig. 4, with the result that regular courses are knit. Whenever during the making of the outer fold of the welt, it is desired to have a fancy stripe made by a course or courses containing float stitch, a chain link containing a low lug 837 on the left side of the chain comes under the pattern chain reading arm 368 and pushes the clutch actuating rod 522 up into the path of the clutch 723. This results in the stitch cam 361 being lowered for two courses and then raised for two courses. However, after the picot edge, the main pattern drum 120, as already mentioned, was racked ahead by the pattern chain, bringing the yarn finger F^1 to its raised position by means of the thrust rod 738 riding upon the cam 347 to permit floating of the heavy yarn 729. As shown in Fig. 9, the thrust rod 460 for the levelling cam still rests on the surface of the low cam 824 and the thrust rod 840 for the auxiliary clearing cam 842 has ridden off the cam 845, causing insertion of the auxiliary clearing cam 842. The parts are therefore in the position shown in Figs. 4, 6 and 9.

With this set-up the needles n^1 with jacks 380 are raised to the clearing level by their jacks, so that they take both yarns, while the jackless needles n^2 , n^3 , which were cleared by the auxiliary clearing cam 842 and then lowered to the tucking level by the levelling cam 822, take only the light yarn 730 from the yarn finger F^2 . The floated yarn, i. e., the heavy yarn 729 coming from the yarn finger F^1 , is thus omitted for two courses on those needles, resulting in the ornamental appearance shown in the upper half of Fig. 2. The floats formed in these two courses on the jackless needles are marked by the reference character 731. After two courses of floats, two courses of regular knitting are made merely by raising the stitch cam 361, and the ornamental structure resulting from this particular four-course cycle of the machine can be repeated to make any desired number of stripes. The low lug 837 on the pattern chain 85 acts as a master control for the location of such stripes.

At the completion of the welt the bights of 70 yarn lying in the transfer jacks are transferred to the cylinder needles, as set forth in the above-mentioned patent to Scott, No. 1,282,958, and the machine is ready to begin the knitting of the leg. Assuming that the machine is going to make the 75 entire leg with the fancy float stitch shown in the

lower part of Fig. 2, the machine will at this point be adjusted as follows. The auxiliary clearing cam 842 which was held out of action during the transfer operation by the cam 848 on the main pattern drum 120, returns to action, its thrust rod 840 dropping down on the surface of the pattern drum. The yarn finger F^1 continues in its raised position, its thrust rod remaining on the cam 847, and the levelling cam 822 is held in by the low cam 849. During the transfer operation the arm 825 was exerting extra pressure on the levelling cam wire-spring 826 because the arm 825 at this point is given extra movement inward in order to cause insertion of another cam during transfer, which is operated from the same thrust rod 460. At the end of the racking movements for the transfer in making an automatic inturned welt, the thrust rod 460 for the levelling cam 822 rests on the low cam 849. By the time the machine has finished the transfer operation and is ready to begin the fancy float stitch in the leg, the pattern disk 480, moving in unison with the pattern drum, has been racked ahead until the cam 482 has come under the pattern shaft reading arm 838, thus raising the actuating rod 522 until its upper end lies in the path of the clutch 723. This actuating rod remains in the path of the clutch and a two-course lowering of the stitch cam 361 alternates with two courses during which the racking means 66, 725 allow the stitch cam 361 to be raised to its normal level. This cam 482 is of sufficient length to remain under the reading arm throughout the leg and the cycle of operation which takes place is similar to that used in the formation of the stripes in the outer fold of the welt, except for the fact that the pattern chain is not in direct control. When the high splice above the heel is reached, the pattern chain is given a rack and the thrust rod 460 controlling the levelling cam 822 rides off the drum cam 849 and the levelling cam is retracted out of the path of the short butt needles n^2 . The yarn finger F^1 maintains its raised position, however, and the long butt jackless needles n^3 continue to float the heavy yarn 729, making the fancy float stitch structure on the front of the stocking. When the heel is reached a rack on the main pattern drum moves the disk cam 482 from under the pattern shaft reader arm 838, allowing the stitch cam 361 to remain in its normal position shown in dotted lines in Fig. 4, the thrust rod 840 for the auxiliary clearing cam 842 riding up on the cam 850, and the yarn finger F^1 is raised by the drum cam 853 and the yarn finger F^2 is also raised out of action by a similar high drum cam, while special yarns for the heel are inserted and the levelling cam 822 is inserted all the way by the drum cam 851. The long butt needles n^3 are raised by the switch cam 415. At the finish of the heel, the levelling cam 822 withdraws again out of the path of the short butt needles but remaining in the path of the long butt needles. This is caused by the thrust rod 460 riding off the cam 851. During this same rack the auxiliary clearing cam 842 comes back into action because its thrust rod 840 drops off the cam 850 down to the surface of the main pattern drum 120 and the yarn fingers F^1 and F^2 are thrown into action again and the other yarn fingers retired. The yarn finger F^1 does not come all the way down to the throat plate, the yarn finger staying in its elevated position as shown in Fig. 4, because its thrust rod 738 lies on the surface of a low drum cam 852. The switch cam also lowers the needles n^3 . The making of the plain sole and patterned instep then follows in a

5 manner similar to the making of the plain high splice and patterned front of the stocking. The reading finger 838 rests on the cam 481 on the disk 480, holding the rod 522 up to engage the clutch 723 and thus lowering the regular clearing cam 361 intermittently to the position shown in solid lines in Fig. 4. The lowering movement of the cam 361 is in the direction shown by the small arrow on the clearing cam 361 in that figure.

At the end of the foot the switch cam 415 raises the long butt needles n^3 above the top center knitting cam 357, as it did at the heel, and reciprocatory knitting begins for the making of the toe. Yarn changes similar to those at the heel can take place at this time. The auxiliary clearing cam 842 is held out of action by the drum cam 845 during the making of the toe.

During the making of the toe, the yarn finger F^1 is raised out of action by a drum cam 854 and the levelling cam 822 is held in action by a low cam 855. The yarn finger F^1 is also out of action in a manner similar to the heel, other yarn being fed to the needles.

I claim:

25 1. A circular knitting machine having independent needles, a clearing cam for said needles, and means for moving said cam from clearing to non-clearing position, in combination with a pattern chain, a lug on said pattern chain for causing said cam moving means to lower the cam from clearing position, mechanism for actuating the cam moving means intermittently, a second lug on the pattern chain, and means actuated by said second lug to connect said cam moving means to said intermittent mechanism to lower the cam from clearing position independently of said first lug.

40 2. A circular knitting machine having independent needles, a clearing cam for said needles, and means for moving said cam from clearing to non-clearing position, in combination with a pattern chain, a lug on said pattern chain for causing said cam moving means to lower the cam from clearing position, mechanism for actuating the cam moving means intermittently, a second lug on the pattern chain, means actuated by said second lug to connect said cam moving means to said intermittent mechanism to lower the cam from clearing position independently of said first lug, and means acting independently of said lugs for causing said cam moving means to lower the cam from clearing position.

45 50

55 3. A circular knitting machine having independent needles, a clearing cam for said needles, and means for moving said cam from clearing to non-clearing position, in combination with a pattern chain, a lug on said pattern chain for causing said cam moving means to lower the cam from clearing position, mechanism for actuating the cam moving means intermittently, a second lug on the pattern chain, means actuated by said second lug to connect said cam moving means to said intermittent mechanism to lower the cam from clearing position independently of said first lug, and means acting independently of said lugs for causing said cam moving means to lower the cam from clearing position, said last mentioned means including a disk racked intermittently by the pattern chain and making one complete revolution for each complete revolution of said pattern chain.

70

4. A circular knitting machine having independent needles, a clearing cam for said needles, and means for moving said cam from clearing to non-clearing position, in combination with

a pattern chain shaft, a sprocket wheel thereon, a pattern chain carried on said sprocket wheel, lugs on said pattern chain for effecting a complete revolution of the pattern chain shaft for each complete revolution of the pattern chain, 80 a second lug on said pattern chain for causing the cam moving means to lower the cam from clearing position, mechanism for actuating the cam moving means intermittently, a third lug on the pattern chain, means actuated by said 85 third lug to connect said cam moving means to said intermittent mechanism to lower the cam from clearing position independently of the other chain lugs, a disk mounted on the pattern chain shaft and rotating therewith to make one complete revolution for each complete revolution of the pattern chain, and spaced cams mounted on the disk and acting independently of the lugs on the pattern chain to lower the cam from clearing 90 position. 95

5. A circular knitting machine having independent needles, a clearing cam for said needles, and means for moving said cam from clearing to non-clearing position, in combination with a pattern chain, a high lug on said pattern chain for causing said cam moving means to lower the cam from clearing position, mechanism for actuating the cam-moving means intermittently, a low lug on said pattern chain, and means actuated by said low lug to connect said cam moving means to said intermittent mechanism to lower the cam from clearing position independently of said high lug. 100 105

6. A circular knitting machine having independent needles, a clearing cam for said needles, and means for moving said cam from clearing to non-clearing position, in combination with a pattern chain, a high lug on said pattern chain for causing said cam moving means to lower the cam from clearing position, mechanism for actuating the cam means intermittently, a low lug on said pattern chain, means actuated by said low lug to connect said cam moving means to said intermittent mechanism to lower the cam from clearing position independently of said high lug, and means acting independently of said lugs for causing said cam moving means to lower the cam from clearing position.

7. A circular knitting machine having independent needles therein, a clearing cam movable from clearing position to tucking position, a pattern chain controlling the operation of the machine, rack and pawl means controlled by said pattern chain, cam means operated by said rack-¹²⁵ing means adapted to control movement of said clearing cam, in combination with a lug on said pattern chain and mechanism actuated directly by said lug to cause lowering of the clearing cam independently of the cam means.¹³⁰

8. A circular knitting machine having independent needles thereon, a clearing cam movable from clearing position to tucking position, a pattern chain controlling the operation of the machine, rack and pawl means controlled by said pattern chain, cam means operated by said rack means adapted to control movement of said clearing cam, a lug on said pattern chain, mechanism actuated directly by said lug to cause lowering of the clearing cam independently of the cam means, and means acting independently of said cam means and lug, for causing the clearing cam to lower from clearing position. 135 140 145

9. A circular knitting machine having a circle of independent needles, a pattern chain controlling the operation of the machine, a clear- 150

- ing cam for said needles, a continuously revolving element having cam means thereon, racking means operated thereby, a clutch adapted to be connected to said racking means and a lever connected to said clutch adapted to lower said clearing cam to tuck level and raise it, in combination with lugs of two or more heights on said pattern chain and means actuated by said pattern chain lugs adapted to connect the clutch to the racking means, the lugs of one height lowering the clearing cam directly and the lugs of another height connecting the clutch to the racking means for intermittent lowering and raising of said clearing cam. 80
- 5 10. A circular knitting machine having a circle of independent needles, a pattern chain controlling the operation of the machine, a clearing cam for said needles, a continuously revolving ele- 85
